[57] CLAIM

The ornamental design for a fishing rod holder, as shown and described.

DESCRIPTION

FIG. 1 is a perspective view from above of my new design for a fishing rod holder with a cord extending therefrom. A fishing rod and reel is shown in broken line for illustration only, and is not part of the claimed invention;

FIG. 2 is a side elevational view thereof of FIG. 1;
FIG. 3 is a side elevational view of the other side thereof FIG. 1;

FIG. 4 is a front elevational view thereof FIG. 1, the rear elevation being a mirror image;

FIG. 5 is a top plan view thereof FIG. 1;

FIG. 6 is a bottom plan view thereof FIG. 1;

FIG. 7 is a perspective view from above of my new design for a fishing rod holder with a sizing insert and a cord extending therefrom. A fishing rod and reel is shown in broken line for illustration only, and is not part of the claimed invention;

FIG. 8 is a side elevational view thereof FIG. 7;

FIG. 9 is a side elevational view of the other side thereof FIG. 7;

FIG. 10 is a front elevational view thereof FIG. 7, the rear elevation being a mirror image;

FIG. 11 is a top plan view thereof FIG. 7; and,

FIG. 12 is a bottom plan view thereof FIG. 7.
